UNITED STATES PATENT OFFICE.

JEREMIAH F. COLLINS, OF BROCKTON, MASSACHUSETTS.

DESIGN FOR A HINGE MEMBER.

SPECIFICATION forming part of Design No. 32,693, dated May 22, 1900.

Application filed August 22, 1899. Serial No. 728,129. Term of patent 14 years.

To all whom it may concern:

Be it known that I, JEREMIAH F. COLLINS, of Brockton, in the county of Plymouth and State of Massachusetts, have invented and 5 produced a new and original Design for a Hinge Member, of which the following is a specification.

This invention relates to a new and original design for a hinge member; and it consists in 10 the novel features of shape and configuration hereinafter fully described and particularly claimed, and clearly illustrated in the drawings.

Reference is to be had to the accompanying 15 one sheet of drawings, forming a part of this specification, in which like characters indicate like parts wherever they occur.

The drawings show my design in a perspective view.

1 represents a tubular hinge member. Said 20 hinge member is formed on one side with an extension 2 and upon its opposite side with an oval-shaped slot 3.

The leading feature of my device consists of a tubular hinge having an extension upon 25 one side and an oval-shaped slot formed in the wall of the tube on the opposite side.

I claim—

The design for a hinge member, substantially as shown and described.

In testimony whereof I have affixed my signature in presence of two witnesses.

JEREMIAH F. COLLINS.

Witnesses:

H. L. ROBBINS,
E. BATCHELDER.
